UNITED STATES PATENT OFFICE

AUGUST E. R. BLOMQUIST, OF CLEVELAND, OHIO

VIBRATING MACHINE

Application filed July 9, 1928. Serial No. 291,375.

This invention relates to improvements in 5 vibrating machines of the class in which an applicator strap or belt, that is adapted for engagement about a part of the body to be treated, is connected to vibrating members or cranks that act to jerk the strap or belt alternately in opposite directions thereby to set up a vibratory action that is imparted to the part of the body wherewith the belt is 10 engaged.

The primary purpose of the invention is to provide a machine of the above mentioned class wherein either or both the speed of the machine and the length of the stroke may be 15 changed by simple and convenient manipulations.

Further objects are to provide a substantial, durable and rigid machine of the class aforesaid that is very efficient; that incorporates mechanism that is relatively simple of 20 construction, positive of action, and convenient of adjustment for changing the speed of the machine; and to provide means, possessing like qualities, for adjusting the stroke 25 of the machine.

With the foregoing and additional objects in view that will become apparent as this description proceeds, the invention may be defined as consisting of the combination and 30 arrangement of elements set out in the claims annexed hereto and illustrated, according to the present preferred embodiment of the invention, in the accompanying drawings.

In the drawings, Fig. 1 is a front elevation, 35 and Fig. 2 a fragmentary side elevation, of my improved vibrating machine; Fig. 3 is a plan view of the machine with the applicator belt or strap shown in broken lines; Fig. 4 is a central vertical section through the 40 machine on the lines 4—4 of Figs. 1, 3 and 5, and on a scale somewhat enlarged over that of the preceding views and in which the middle portion of the machine is broken away so as to shorten the view and permit of the 45 larger scale; Fig. 5 is a horizontal section

that is taken substantially on the line 5—5 of Fig. 4; Fig. 6 is a detail of the gearing appearing in Fig. 5 and showing the driver shifted to its position opposite that illustrated in the preceding figure; Fig. 7 is an 50 end view of one of the crank disks and its pin, on a further enlarged scale; Fig. 8 is a section on the correspondingly numbered line of Fig. 7; and Figs. 9 and 10 are sections on the line a—a of Fig. 8, the former being 55 taken as though looking in the direction of the arrows 9, and the latter as in the direction of the arrows 10.

The machine is of the pedestal type and the frame structure thereof includes a base 60 1, a column 2, and a gear casing 3. The base is hollow and, generally, of conical shape, and its under side is formed with sockets 5 within which pads 6 of rubber or other suitable material are held by means of clamping 65 bolts 7.

An electric motor 10 is disposed within the base 1 with its armature shaft 11 substantially coincident with the vertical axis of the base. The motor may be supported by elongated screws 12 whose upper ends are screwed 70 into lugs 13 that are shown as formed integral with the base, the said screws 12 preferably being those which serve to hold the parts of the motor casing together. 75

Fitted to the top of the base 1, and secured thereto as by means of cap screws 15, is the lower end of the hollow column 2. The upper end of this column has a circular opening in which the cylindrical extension 16 of a 80 gear casing 3 is secured. The body portion of the gear casing is, generally, in the shape of a bowl and is surmounted by a cover 17 that is held to the casing by screws 18. Adjacent its forward side, the casing 3 is formed with laterally extending hollow bosses 20. Fixed within each of said bosses 20 is a cylindrical shell 21 having, intermediate its ends, an internal flange 22 that supports an anti-friction bearing 23. Clamped between the 85 90

outer side of the flange 22 of each of the shells 21 and a ring nut 24 that is screwed into the outer end of the shell is a retainer 25 for an oil ring 26 of suitable packing material. 5 Rotatably supported within the ring nuts 24 and retainers 25, by the bearings 23, are shafts 28 that carry crank disks 29 at their outer ends, said shafts having grooves 30 that are occupied by the inner edges of the oil rings 26. 10 Collars 31 are pinned or otherwise secured to the shafts 28 inwardly of the bearings 23 for retaining the shafts against outward movement. Mounted upon, and keyed or otherwise secured to, the reduced inner ends of the crank shafts 28 is a unit 35 incorporating axially spaced worm wheels 36 and 37 that are of different diameters.

The cylindrical extension 16 of the casing 3 has a correspondingly shaped bore where 20 in is journaled a hollow cylindrical block 40 that is provided with diametrically opposed tapered sockets 41 for the reception of the conical end 42 of a locking screw 43 that is threaded adjacent its outer end and operates within a tapped hole in the casing 3, the screw being equipped with a knurled head 44. Journaled within anti-friction bearings 45 that are suitably fitted within the upper and lower ends of the block 40 25 is a shaft 46 that is equipped with a worm 47 for cooperation with the previously mentioned worm wheels 36 and 37 of the unit 35. A packing device 48 seals the joint between the lower end of the shaft 46 and the block 40 so that a quantity of suitable lubricant 30 may be retained in the casing.

The shaft 46 is driven from the motor shaft 11, in the present instance, through the intervention of a flexible shaft 50, the joined 40 ends of the base 1 and column 2 having aligned apertures 51 for the accommodation of the flexible shaft. An electric switch 52 is shown as mounted within the upper front portion of the column 2, and wires are led 45 therefrom, through an opening 53 in the column, downwardly through the column and through the openings 51 to the motor, but for the sake of clearance these wires are omitted from the drawings.

50 A spindle 60 is journaled within a central hollow boss of the cover 17 and at its upper end is equipped with an operating handle 61. Secured to the lower end of the spindle is an arm 62 (Figs. 4, 5 and 6) whose free 55 end is provided with an aperture within which is journaled the upper end of the shaft 46 that carries the worm 47.

From the foregoing description it is evident that when the switch 52 is closed and 60 the motor 10 energized as a consequence thereof, the rotation of the motor shaft will be transmitted through the flexible shaft 50 to the shaft 46, and thence, through the worm 47 and one or the other of the worm wheels 65 66 or 37 to the crank shafts 28. Assuming

that the motor runs at a substantially constant speed, the speed of the cranks may be changed by first retracting the locking screw 43 so as to withdraw its inner end from the socket 41 of the block 40 that it then occupies, and then turning the spindle 60 by means of the operating handle 61 to swing the worm 47 out of engagement with one worm wheel and into mesh with the other. The doing of this rotates the block 40 through 180 degrees and presents the other recess 41 of said block in receiving relation to the locking screw 43, whereupon said screw may be turned by the knob 44 to project its inner end into said recess.

80 In addition to changing the speed of machines of the class in question, it is desirable to change the length of the stroke. This I accomplish by making the crank pins shiftable toward and from the center of the crank disks 29.

Each crank pin 65 extends from a relatively flat circular head 66 of a stud 67 that is journaled within a recess 68 of the corresponding crank disk 29, the peripheral portion of the head 66 having a plain inner face that engages a flat annular surface on the crank disk. The inner face of the head 66 has a plurality of depressions 70 that are spaced apart like distances circumferentially of the head, and a ball 71 that is contained, with a spring 72, within a recess in the crank disk, is urged outwardly by said spring into any one of the depressions 70 that is brought into register with the ball. This is an indexing means for enabling both crank pins 65 to be similarly adjusted with respect to their crank disks; but the crank pins are adapted to be held in fixed relation to their disks by means which I shall now describe. The inner end of each of the studs 67 has a circumferential groove whose walls, especially their inner walls, are beveled, as shown at 75. Operating within a radial bore of each crank disk is a bolt 76 whose inner end is shaped for cooperation with the tapered wall 75 of the stud 67, and said bolt is adapted to be forced inwardly by means of a screw 77 that is threaded into the enlarged tapped outer end of the bore that is occupied by said bolt. When the bolt is forced inwardly it cams the stud 67 axially of the recess 68 and draws its head 66 into such firm contact with the underlying portion of the crank disk 29 as to frictionally hold the crank 100 disk 29 against displacement from the position wherein it is yieldingly held by the ball 71.

105 Having thus described my invention, what I claim is:—

1. In a vibrating machine, the combination of a vibrating element, mechanism for vibrating the same including axially spaced gears, a member rotatable on an axis intermediate the planes of said gears, power transmitting means supported by said member 110

and adapted to be swung through an arc concentric with the axis of rotation of said member into driving engagement with either of said gears by the oscillation of said member, means rotatable on an axis substantially coincident with that of the member for oscillating said member through the intervention of the power transmitting means, and driving mechanism having operative connection with said power transmitting means.

2. In a vibrating machine, the combination of a supporting structure, vibrating mechanism sustained thereby and including axially spaced gears, a member supported by the structure for rotation on an axis intermediate the planes of said gears, power transmitting means carried by said member and adapted to be swung through an arc concentric with the axis of rotation of said member into driving engagement with either of said gears by the oscillation of said member, means supported by the structure for rotation substantially on the axis of said member and by means of which the member is adapted to be rotated through the intervention of the power transmitting means, driving mechanism, and operative connections between said mechanism and the power transmitting means.

3. In a vibrating machine, the combination of a pedestal-like supporting structure, driving mechanism within the base of said structure and having a driving shaft whose axis is substantially coincident with that of the structure, a member supported by the upper portion of said structure for rotation on an axis substantially coincident with that of the structure, a driver and its shaft rotatably supported by said member with its axis substantially vertical and eccentric with respect to that of the member, vibrating mechanism sustained by the structure and involving gears spaced apart along a common axis that is located to one side of and disposed at substantially right angles to the axis of the casing, the driver being adapted to be shifted into engagement with either of said gears by the oscillation of said member, and flexible driving connections between the shaft of said driver and the shaft of the aforesaid driving mechanism.

4. In a vibrating machine, the combination of a pedestal-like supporting structure, driving mechanism within the base of said structure and having a driving shaft whose axis is substantially coincident with that of the structure, a member supported by the upper portion of said structure for rotation on an axis substantially coincident with that of the structure, a shaft rotatably supported by said member with its axis substantially vertical and eccentric with respect to that of the member, a driver carried by said shaft, vibrating mechanism sustained by the structure and involving gears spaced apart along

a common axis that is located to one side of and disposed at substantially right angles to the axis of the casing, said driver being adapted to be shifted into engagement with either of said gears by the oscillation of said member, means for retaining said member in the respective positions it occupies when the driver is in engagement with the said gears, and driving connections between the shaft of said driver and the shaft of the aforesaid driving mechanism and which is of such nature as to permit of the oscillation of the aforesaid member.

5. In a vibrating machine, the combination of a pedestal-like supporting structure, driving mechanism within the base of said structure and having a driving shaft whose axis is substantially coincident with that of the structure, a member supported by the upper portion of said structure for rotation on an axis substantially coincident with that of the structure, a driver and its shaft rotatably supported by said member with its axis substantially vertical and eccentric with respect to that of the member, vibrating mechanism sustained by the structure and involving gears spaced apart along a common axis that is located to one side of and is disposed at substantially right angles to the axis of the casing, the driver being adapted to be shifted into engagement with either of said gears by the oscillation of said member, means for retaining said member in the respective positions it occupies when the driver is in engagement with the said gears, driving connections between the shaft of said driver and the shaft of the aforesaid driving mechanism and which is of such nature as to permit of the oscillation of the aforesaid member, a spindle journaled within the supporting structure for rotation on an axis substantially coincident with that of said member, and connections through which the member is adapted to be rotated by said spindle through the intervention of the driver shaft.

6. In a vibrating machine, the combination of a supporting structure comprising a base, pedestal, and surmounting casing, cranks disposed on the opposite sides of said casing and having a common rotating axis, a member within the casing and connected to the cranks for driving the same, said member involving axially spaced gears, a member journaled within the supporting structure substantially on the vertical axis of the casing and between the planes of said gears, a shaft journaled within said member and having its axis eccentric with respect to that of the member, a driver on said shaft for cooperation with said gears, said members being adapted to be rotated in one direction to engage the driver with one of the gears, and in the opposite direction to engage the driver with the other gear, means for retaining the member in either of its extreme positions, a

spindle journaled within the top of the casing with its axis substantially coincident with the axis of the aforesaid member, connections through which said member is adapted to be oscillated through the intervention of the aforesaid shaft, an operating handle carried by the spindle above the casing, driving mechanism within the base, and flexible driving connections between said mechanism and the aforesaid shaft, said connections being housed within the pedestal of the structure.

10 In testimony whereof, I hereunto affix my signature.

AUGUST E. R. BLOMQUIST.
